UNITED STATES PATENT OFFICE

94,715

DESIGN FOR A COMBINED CLOCK AND MIRROR

Edgar L. Vail, New York, N. Y., and Joseph Berge, East Orange, N. J.

Application December 1, 1934, Serial No. 54,225

Term of patent 7 years

To all whom it may concern:

Be it known that we, Edgar L. Vail, a citizen of the United States, residing in the city of New York, county of New York, and State of New York, and Joseph Berge, a citizen of the United States, residing in the city of East Orange, county of Essex, and State of New Jersey, have invented a new, original, and ornamental Design for a Combined Clock and Mirror, of which the following is a specification, reference being had to the accompanying drawing forming a part thereof.

We claim:

The ornamental design for a combined clock and mirror as shown.

EDGAR L. VAIL.
JOSEPH BERGE.
